UNITED STATES PATENT OFFICE

ELDRIDGE R. FERRIMORE JOHNSON, OF MOORESTOWN, NEW JERSEY, ASSIGNOR TO MECHANICAL IMPROVEMENTS CORPORATION, OF CAMDEN, NEW JERSEY, A CORPORATION OF NEW JERSEY

LAUNCHING DEVICE FOR LIFE PRESERVERS

Application filed March 23, 1932. Serial No. 600,765.

This invention relates to holding and launching means for life preservers and more particularly to devices embodying a life ring or buoy having attached thereto a torch, 5 smoke producing device, or the like which operates when it is dropped in the water with the life ring.

The usual type of marine torch or smoke producing device embodies a sealed container having a removable or detachable portion so that the seal of the container can be broken before it is thrown in the water with the life ring, the torch being usually connected with the life ring by a lanyard. The container 10 holds some suitable substance which is acted upon by the water entering after the seal is broken to produce a visible signal indicating the position of the life ring. Ordinarily the life ring and the signalling device, hereinafter referred to as a torch, are lashed to the rail or other part of the ship and the lashings must be cut before the ring can be used, the seal of the container being broken in detaching it from the rail. But knives for cutting the lashings are not always handy when needed, and the loss of minutes or even seconds in getting the ring into the water may mean the difference between life and death, 15 since a ship moving at say fifteen knots will travel approximately five hundred yards per minute. Time is therefore of the essence in releasing the life ring and torch, and hence it has been proposed heretofore to mount the ring and the torch in suitable supports or 20 housings so that they can be released by actuation of a handle or other operating member. It is necessary, however, that the life ring and torch be firmly secured to withstand rough usage and heavy weather, while at the same time means must be provided for insuring a smooth and positive delivery of the ring and torch and positive breaking of the torch seal 25 instantaneously and without danger of sticking or binding of the parts.

One of the objects of the present invention is to provide novel means for holding and launching a life ring and torch which means retains the ring and torch securely in position but releases and launches the ring and torch and breaks the torch seal smoothly and

instantaneously with a single continuous manual operation such as pulling a cable.

Another object is to provide novel means for holding and launching a life ring and torch wherein the ring and torch are not only 35 released but are both positively ejected from the holder and the torch seal positively broken by the actuation of a single operating member.

One embodiment of the invention has been 40 illustrated in the accompanying drawings but it is to be expressly understood that said drawings are for purposes of illustration only and are not to be construed as a definition of the limits of the invention, reference being had to the appended claims for this purpose.

In the drawings,

Fig. 1 is a side view of an apparatus embodying the invention and mounted on the 45 rail of a ship;

Fig. 2 is an end view of the apparatus shown in Fig. 1;

Fig. 3 is a detail of part of the apparatus;

Fig. 4 is a view of the side of apparatus 50 opposite from that shown in Fig. 1;

Fig. 5 is an end view partly in section of the apparatus; and

Fig. 6 is a detail view of a portion of the 55 apparatus.

The life ring is preferably mounted releasably in a holder of any suitable type, size and shape, which may be secured for example to the rail or other part of a ship. 60 In the form shown, the holder 1 is of metal or any other suitable material and is generally U-shaped as shown in Figs. 1 and 4, the cross section of said housing being also U-shaped as shown at the upper portion of Fig. 5. On its side adjacent the ship, the holder is provided with ribs 2 to which are secured suitable clamps 3 for securing the holder on a rail 4 of the ship which rail extends between adjacent stanchions 5. The 65 ribs 2 are also provided with brackets 6 that are secured in any suitable way to the side 7 of the ship, so that the holder is rigidly supported. It will be understood, however, that any other suitable means may be provided 80

for securing the holder to the ship, or to a stationary dock or the like.

The life ring may be of any suitable type and in the form shown comprises a ring 8 of cork or other buoyant material covered with canvas 9 and provided if desired with the usual hand line 56, the holder being of proper size to receive the ring. Connected to the ring 8 in a manner described herein-after is a marine torch 10 which also may be of any suitable or known type. For the purposes of illustration, said torch comprises a normally sealed container in which is a quantity of suitable material such as carbide 15 which produces an inflammable gas when mixed with water. The life ring 8 is securely held in the holder 1 by suitable means which can be released on actuation of an operating member, preferably by a securing 20 or holding strap secured either to the ring or holder and releasably held at one end so as to support the ring in the holder. In the form shown a reinforcing strap 11 surrounds the life ring at one point in its circumference and the securing or holding strap 12 is secured in any suitable manner to the reinforcing strap 11, the free end of said strap 12 being preferably flexible and provided at its end with an eye 13. Secured to 25 the holder in any suitable manner is a bracket 14 that is provided with an opening 15 through which the end of the strap 12 extends, the eye 13 of the strap being disposed between and in alignment with openings 16 30 in two rings 17 preferably formed integrally with the bracket 14. A locking pin 18 extends through the opening 16 and the eye 13 and normally holds the life ring in the holder 1 in the position illustrated in the 35 drawings.

The torch 10 is connected with the life ring by a lanyard 19 which as shown is attached at one end to an eye 20 on the torch and is looped around and secured to the strap 45 12 at 21 as shown in Figs. 1 and 5. Suitable means are provided for securing the torch in the holder and from which the torch is quickly releasable. As shown, a housing bracket 22 is secured to the bracket 14, said 50 bracket 22 being provided with a plurality of depending leaf springs 23 which normally hold the torch in the position shown in the drawings.

With apparatus of this type, the necessary 55 operations in releasing and launching the life ring and torch are that the seal on the torch must be broken and the life ring and torch must be released from the holding means described above, and preferably both 60 the life ring and torch should be positively ejected from the holding means by manually operated ejectors. As above stated, all of these operations should be performed freely and in sequence by the action of a single 65 operating member. Hence means are pro-

vided for breaking the seal on the torch, for withdrawing the locking pin 18 from engagement in the eye 13 of the strap 12, for positively ejecting the life ring 8 from the holder 1, and for positively ejecting the 70 torch 10 from the holding springs 23, all of said means being actuated by a suitable operating member such as a cable in such a way that pulling on the cable performs the desired operations in sequence and effects a 75 smooth and positive delivery of the ring and torch.

For purposes of illustration, the seal on the torch may be formed by a cap 24 of any suitable type that is soldered to the top of the torch so as normally to close an opening 25 (Fig. 6), the cap being adapted to break away from the torch so that when the torch is dropped in the water the opening 25 is no longer sealed. To this end an eye 26 is secured to the cap 24 and a ring 27 passes through the eye 26 and around a lug or pin 28 on a lever 29 that is suitably pivoted at 30 on a bracket 31 secured to the top of the torch housing bracket 22. The end of the lever 29 is forked at 32 and surrounds an actuating cable 33 so that the lever may be swung by pulling on the cable to break the cap 24 from the torch. As shown, the actuating cable 33 is split at 34, the branches 35 and 36 thereof extending upwardly to the top of the holder 1 and passing through an opening 37 formed in a bracket 38 secured to the top of said holder in any suitable manner. The cable 35 terminates in a loop or ring 39 at the top of the housing, which loop or ring may be grasped to launch the ring and torch. The cable 36 extends upwardly to any other desired position on the ship so that the mechanism can be actuated therefrom.

The first action desired on pulling the cable 33 is to swing the lever 29 to break the torch seal as described above, and the second desired action is to release the locking pin 18, these operations taking place before the positive ejection of the torch and ring. To these ends the cable 33 in the form shown passes through a plurality of openings formed in a cable block 40 (Fig. 3) which cable block as shown in Fig. 1 engages the forked end 32 of the lever 29. As shown in Fig. 3 the cable passes first through an opening 41 in the block 40, then through an eye 42 formed at one end of the locking pin 18, and then through openings 43 and 44 of the block 40. From the block 40 the cable passes around a pulley 45, which as shown is mounted in a bracket 45' secured to the bracket 14, and slack is normally provided in the cable at 46 so that the operations of breaking the seal on the torch and raising the locking pin 18 take place before the cable is pulled taut around the pulley 45 to actuate the ejecting mechanism hereinafter described.

In the form shown, the life ring is ejected from the holder 1 by means of a curved ejector 47 having an eye 48 to which the cable 33 is attached. The ejector 47 normally lies in a groove 49 formed in the holder as shown in Fig. 5, the upper end of the ejector being curved over the top of the life ring. Preferably the ejector is provided with a centering pin 50 which as shown is adapted to enter a pocket 51 formed in the bracket 38 at the top of the holder. After the pin 18 has been pulled out of the eye 13, the life ring is free to fall by gravity from the holder, but continued pulling on the cable 33 takes up the slack at 46 and actuates the ejector 47 to displace the life ring positively from the holder and to give it an initial start so that there is no danger of the ring failing to drop because of sticking or binding in the holder.

Since the torch 10 is connected with the life ring by the lanyard 19, the ring would tend to pull the torch from the springs 23 on dropping free of the holder. Preferably however the lanyard 19 is of considerable length, and if the torch should stick in its housing bracket, the life ring would be left hanging therefrom. Accordingly, means are also provided for positively ejecting or pulling the torch 10 from the springs 23, said means in the form shown being actuated by downward movement of the life ring 8 while it is still under the positive control of the ejector 47. Referring particularly to Figs. 5 and 6, a torch ejector 52 is inserted in the holding bracket 22, said ejector being provided with forked arms 53 which engage over the top of the torch and embrace the cap 24 as shown in Fig. 6. An eye 54 is formed in the lower end of the ejector 52, and a lanyard 55 is connected to said eye and also to the releasing means for the life ring 8 in any suitable manner. As clearly shown in Fig. 1, the lanyard 19 which is looped about the strap 12 at 21 may be continued to form the lanyard 55, although separate lanyards may be provided if desired and the lanyard 55 may be connected to the life ring in any other suitable manner.

The operation of the apparatus will be clear from the foregoing description and may be summarized as follows: The life ring and torch are normally in the position shown in the drawings, wherein the life ring is positively supported in the holder by the engagement of the locking pin 18 in the eye 13 and the torch 10 is held in the housing bracket 22 by the springs 23. Preferably the lanyard 19 is coiled loosely about the rings 17 on the bracket 14, as shown in Fig. 1. When it is desired to use the life ring, the ring 39 is grasped and pulled by the operator. The first action which takes place is the raising of the lever 29 about its pivot 30, by virtue of the engagement of the cable block 40 with the end of said lever, this action as described

above breaking the cap 24 away from the torch as shown in Fig. 6. During the raising of the lever 29, the pin 18 is also being raised, and after the torch seal has been broken, the pin 18 is disengaged from the eye 13 of the strap 12, the life ring 8 being now free to drop by gravity from the holder. Thus far the ejector 47 has not been actuated due to the slack at 46 in the cable 33. Just as the pin 18 is released from the eye 13 however, the slack in the cable is taken up and the ejector 47 is pulled sharply downwardly, displacing the life ring positively from the holder. It will be seen that the movement of the ejector may continue until the end thereof reaches the pulley 45, at which time the ring is substantially free from the holder.

The downward movement of the ring takes up the slack in the lanyard 55 before the movement of the ejector 47 is finished, so that the pull on the ring 39 is transmitted positively to the ejector 52 and the torch is jerked free of the springs 23. This arrangement insures that the torch shall be positively ejected and also prevents the torch sticking in the housing bracket and thus holding the life ring against delivery from the holder. The life ring, together with the strap 12, lanyard 55, ejector 52 and torch 10 drop freely from the housing, the coiled lanyard 19 running freely from the rings 17. To restore the apparatus to condition for further use, the used torch 10 is replaced by a new torch. The ejector 47 is properly positioned in the holder in the position shown in the drawings and the life ring is inserted in the holder, the end of the strap 12 being passed through the opening 15 and the locking pin 18 being inserted in the eye 13 of the strap. The ejector 52 is now inserted in the torch holding bracket 22 and the new torch is then inserted in the bracket, the ring 27 of the torch being engaged over the lug 28 on the lever 29. The lanyard 19 is then coiled loosely about the rings 17, the cable 33 and cable block 40 are arranged as shown in the drawings, and the apparatus is ready for a second operation.

It will be observed that the torch and ring are securely mounted and held against accidental displacement. This is an important characteristic of devices of this type since the life ring is only used in case of an emergency which may not occur over a period of years. This fact, however, also renders it important to provide means for positively ejecting the torch and ring from the holding means to prevent sticking, binding, adhesion, etc., of the various parts of the apparatus after being secured as shown and exposed to the elements over long periods. The operation of launching the device is simple and substantially instantaneous, it being only necessary to grasp and pull a single operating member. As described above, a single smooth and complete pull on the operating member

effects the complete sequence of operations required to launch the device properly.

It will be understood that the invention is not limited to the form described and illustrated in the drawings, but is capable of a variety of physical expressions. Moreover, changes may be made in the details of construction, form and arrangement of the parts without departing from the spirit of the invention. For example the operating member may comprise a handle or lever instead of a pull ring; the arrangement of the cable which effects the desired operations may be varied; and equivalent mechanical devices may be employed in place of those described, as for example in place of the lever which breaks the torch seal, the cable block and pulley, the form of the ejectors, etc. Reference is therefore to be had to the appended 10 claims for a definition of the limits of the invention.

What is claimed is:

1. In apparatus of the class described, the combination of a life ring and a torch having a breakable seal, holding means for said ring and torch, releasable means for securing said ring and torch in said holding means, means for breaking the torch seal, means for positively ejecting said ring and torch from said holding means, a common operating element, and operative connections between said element and said seal breaking means, said releasable means, and said ejecting means.

2. In apparatus of the class described, the combination of a life ring and a torch having a breakable seal, holding means for said ring and torch, releasable means for securing said ring and torch in said holding means, means for breaking the torch seal, means for positively ejecting said ring and torch from said holding means, an operating cable, and connections between said cable and said seal breaking means, said releasing means and said ejecting means whereby a pull on said cable effects the breaking of the seal and the release of said securing means and thereafter the positive delivery of said ring and torch from said holding means.

3. In apparatus of the class described, the combination of a holder, a life ring, releasable means for holding said life ring in said holder, means for positively ejecting said life ring from said holder, an operating element, and operative connections between said element and said releasing and ejecting means whereby said life ring is released and ejected from said holder on actuation of said element.

4. In apparatus of the class described, the combination of a holder, a life ring, a locking device for securing said life ring in the holder, an ejector for positively discharging the life ring from the holder, and an operating cable connected to said locking means and to said ejector, whereby pulling on said

cable releases the locking means and positively ejects the life ring from the holder.

5. In apparatus of the class described, the combination of a holder, a life ring in said holder, a strap connected to the life ring and having an eye formed therein, a locking member carried by the holder and normally passing through said eye to hold the life ring in the holder, an ejector for discharging the life ring from the holder, and an operating cable connected to said locking member and to said ejector whereby movement of the cable removes the locking member from the eye to release the ring and moves the ejector to discharge the ring positively from the holder.

6. In apparatus of the class described, the combination of a holder, a life ring in said holder, a strap connected to the life ring and having an eye formed therein, a locking member carried by the holder and normally passing through said eye to hold the life ring in the holder, an ejector for discharging the life ring from the holder, and operating means for releasing the locking member from said eye and operating said ejector to discharge the life ring from the holder.

7. In apparatus of the class described, the combination of an inverted U-shaped holder, a life ring therein, a holding strap supporting said life ring and having an eye formed therein, a bracket extending across the legs of the U-shaped holder, a locking pin carried on said bracket and passing through the eye in said strap, an ejector in said holder and engaging the upper portion of the life ring, and an operating cable secured at one end to said ejector and at a point intermediate its ends to said locking pin whereby pulling on the other end of the cable removes the pin from the eye of the holding strap and moves the ejector to discharge the ring from the holder.

8. In apparatus of the class described, the combination of a holder, a life ring, locking means for holding said life ring in the holder, an ejector for discharging the life ring from the holder, a torch connected with the life ring and releasably mounted on said holder, and operating means operatively connected with said locking means and with said life ring ejector.

9. In apparatus of the class described, the combination of a holder, a life ring, locking means for holding the life ring in the holder, a torch connected with the life ring, resilient means for holding the torch on the holder, a life ring ejector, and operating means operatively connected with said locking means and said ejector.

10. In apparatus of the class described, the combination of a holder, a life ring therein, locking means for holding the life ring in the holder, a life ring ejector, a torch, means for releasably securing the torch to the holder,

5 a lanyard connecting the torch with the life ring, a torch ejector connected to the life ring locking means and normally engaging the torch, and operating means connected with said locking means and said life ring ejector.

11. In apparatus of the class described, the combination of a holder, a life ring, locking means for holding the life ring in said holder, an ejector for discharging the life ring from said holder, a torch connected with the life ring and releasably mounted on said holder, and an operating cable connected with said locking means and ejector whereby pulling on said cable releases the locking means and 15 discharges the ring and torch positively from said holder.

12. In apparatus of the class described, the combination of a holder, a life ring, locking means for holding the life ring in said holder, 20 an ejector for discharging the life ring from said holder, a torch connected with the life ring and releasably mounted on said holder, a torch ejector connected to the life ring locking means and normally engaging said torch, 25 and an operating cable connected with said locking means and ring ejector whereby pulling on the cable releases said locking means and positively operates said ring ejector and torch ejector.

30 13. In apparatus of the class described, the combination of a holder, a life ring, locking means for holding the life ring in the holder, a life ring ejector, a torch releasably carried on the holder and having a breakable seal, 35 a seal breaking member, means connecting the torch with the life ring, and an operating member connected with said seal breaking member, said locking means and said ejector.

14. In apparatus of the class described, the 40 combination of a holder, a life ring, locking means for holding the life ring in the holder, a life ring ejector, a torch releasably carried on the holder and having a breakable seal, a seal breaking member, means connecting the 45 torch and ring, and an operating cable connected with said member, locking means and ejector whereby pulling on said cable breaks the torch seal and releases the locking means and thereafter positively operates said 50 ejector.

15. In apparatus of the class described, the combination of a holder, a life ring, locking means for holding the life ring in the holder, a life ring ejector, a torch releasably carried on the holder and having a breakable seal, a seal breaking member, a lanyard connecting said torch and life ring, a torch ejector connected with said life ring locking means and normally engaging said torch, and an operating cable connected with said member, locking means and life ring ejector whereby pulling on said cable breaks the torch seal and releases the locking means and positively 55 operates said ring ejector and said torch ejector.

16. In apparatus of the class described, the combination of a holder, a life ring therein, a holding strap connected to the life ring and having an eye formed therein, a locking pin carried by the holder and normally passing through said eye, an ejector for discharging the life ring from the holder, a torch having a breakable seal and releasably carried on the holder, an operating lever connected with the breakable seal portion of the torch, means connecting the torch with the life ring, and an operating member connected with said lever, locking pin and ejector. 70

17. In apparatus of the class described, the combination of a holder, a life ring therein, a holding strap connected to the life ring and having an eye formed therein, a locking pin carried on the holder and passing through said eye, an ejector for discharging the life ring from the holder, a torch having a breakable seal and releasably carried on said holder, a lever pivoted on the holder and operatively connected with the breakable portion of the torch seal, a lanyard connecting the torch with the life ring, a torch ejector connected to the life ring and normally engaging the torch, and an operating cable connected with said lever, locking pin and life ring ejector. 85

18. In apparatus of the class described, the combination of a holder, a life ring, releasable means for holding the life ring in the holder, an ejector for positively discharging the life ring from the holder, an operating member, and connections between said operating member and said releasable means and ejector, said connections including lost motion whereby the life ring is fully released before the ejector is actuated. 90

19. In apparatus of the class described, the combination of a holder, a life ring, releasable means for holding the life ring in the holder, an ejector for positively discharging the life ring from the holder, and an operating cable connected to said releasable means and ejector and normally having slack between said connections whereby pulling on said cable first releases said life ring and after the ring is fully released operates said 100 ejector. 110

20. In apparatus of the class described, the combination of a holder, a life ring therein, a holding strap connected to said ring and having an eye formed therein, a locking member carried by said holder and extending through said eye, a life ring ejector, and operating means for withdrawing said locking member from said eye and operating said ejector, said operating means providing lost motion whereby said member is fully withdrawn before the ejector is actuated. 115

21. In apparatus of the class described, the combination of a holder, a life ring therein, a holding strap connected to said ring and having an eye formed therein, a locking 120

125

130

member carried by said holder and extending through said eye, a life ring ejector, and an operating cable connected with said locking member and ejector and normally having slack between said connections whereby pulling on said cable fully withdraws said locking member from said eye and thereafter operates said ejector.

22. In apparatus of the class described, the combination of a holder, a life ring, locking means for holding the life ring in the holder, a life ring ejector, a torch releasably carried on the holder and having a breakable seal, a seal breaking member, a lanyard connecting said torch and life ring, a torch ejector connected with said life ring locking means and normally engaging said torch, and an operating cable connected with said member, locking means and life ring ejector and normally having slack between its connections to said member and locking means and its connection to said ejector whereby pulling on said cable positively operates said member and releases said locking means and thereafter positively operates said ring ejector and said torch ejector.

23. In apparatus of the class described, the combination with a life ring, releasable holding means therefor, ejecting means for discharging the ring, a torch connected to the ring and having a breakable seal, and a seal breaking member, of an operating cable adapted for a single continuous pull, said cable being connected to said member and releasable holding means and to said ejector and having slack to be taken up before pulling on said ejector.

In testimony whereof I have signed this specification.

ELDRIDGE R. FERRIMORE JOHNSON.
